Primary Examiner — Ruth McInroy*(74) Attorney, Agent, or Firm* — Barnes & Thornburg LLP(57) CLAIM

We claim the ornamental design for a football helmet, as shown and described.

DESCRIPTION

FIG. 1 is a perspective view of a football helmet showing our new design;

FIG. 2 is a front view thereof;

FIG. 3 is a side view thereof;

FIG. 4 is a top view thereof;

FIG. 5 is a rear view thereof; and,

FIG. 6 is a bottom view thereof.

The details shown in broken lines form no part of the claimed design.

1 Claim, 6 Drawing Sheets# US D856,601 S
